UNITED STATES PATENT OFFICE.

WILLIAM B. THOMPSON, OF LOS GATOS, CALIFORNIA.

AUTOMOBILE-SIGNAL.

1,331,832.

Specification of Letters Patent. Patented Feb. 24, 1920.

Application filed July 24, 1918. Serial No. 246,462.

To all whom it may concern:

Be it known that I, WILLIAM B. THOMPSON, a citizen of the United States, residing at Los Gatos, in the county of Santa Clara and State of California, have invented certain new and useful Improvements in Automobile-Signals; and I do hereby declare the following to be a full, clear, and exact description of the invention, such as will enable others skilled in the art to which it appertains to make and use the same.

This invention relates to automobile signals, and has for its prime object to provide a novel and improved signal of this character which can be easily and conveniently operated by the driver to indicate the fact that he intends to steer the vehicle to one side or stop.

A further object of the invention is to provide the signal with novel illuminating means which may be used when desired to indicate the intentions to turn or stop at night.

With these and other objects in view as will appear as the description proceeds, the invention comprises the various novel features of construction, combination and arrangement of parts as will be fully described hereinafter and afterward specifically claimed.

Referring to the drawings,

Figure 1 represents a front elevation of the signals supported upon the vehicle dashboard, one of said signals having been actuated to indicate turning to the right.

Fig. 2 represents a side elevation of the signal arranged in inoperative position.

Fig. 3 represents a vertical sectional view through one of the signal devices, the parts thereof being arranged in actuated or indicating position.

Fig. 4 represents a sectional plan view indicated by the line 4-4 on Fig. 3.

Fig. 5 represents a similar view but showing the parts in normal position.

In practice, applicant proposes to use a signaling device on each side of the vehicle wind shield and since each of these devices are identical in construction and method of operation, it is believed that a detail description of one will suffice for both.

In order that the construction and operation of the signal may be readily comprehended by those skilled in the art to which the invention relates, I have illustrated the preferred embodiment of the invention in

the accompanying drawings and will now proceed to fully describe the same in connection with said drawings, in which 1 is the vehicle dash upon the upper edge of 60 which is mounted a cushion strip 2 and a supporting bar 3. A hollow post 4 rises from one end of the supporting bar 3 and carries at its upper end a lamp bracket 5 which has its apertured end 6 positioned over 65 the upper end of the post 4.

A collar 7 is threaded over the upper end of the post and serves to hold the bracket in position upon the annular shoulder 8 of the post. 9 is a closure cap threadedly connected to the upper end of the post and provided with a central socket 10 into which is threaded the lower end of a standard 11 which rises upwardly and is provided with an apertured upper end 12 for attachment to 75 the vehicle top 13. This connection can be made in any suitable or well known manner, whereby the top can be quickly and readily disconnected from the standard. The collar 7 carries an upstanding bracket arm 14 to 80 pivotally support the wind shield 15 at a point intermediate each end.

16 is a box conveniently mounted on and intermediate the ends of the supporting bar 3, as clearly shown in Fig. 1, said switch 85 box being connected to each of the posts 4 by a tubular casing 17. An actuating lever 18 is pivotally mounted, as at 19, in each end of the switch box and embodies a quadrilateral segment 20.

A link 22 is mounted within and through the tubular casing 17 and has a U-shaped inner end 23 slidably mounted within the switch box and in such a manner as to receive the segment 20. The other end of the 95 link is disposed at an angle, as at 24, and is pivotally connected as at 25 on a segment 26 fixed on the lower end of a rock shaft 27 mounted within the post 4. 28 is a bearing plate mounted in the supporting bar 3 100 and through which the lower reduced end 29 of the rock shaft is positioned.

The bracket arm 5 supports a signal lamp, indicated as a whole by the letter L, and a direction indicator I. The lamp embodies 105 a casing comprising a bottom 33 and an upper part 34 which may be detachably connected to the bottom in any suitable manner, such as by bayonet slots or the like.

The upper part of the casing 34 embodies 110 an upper and lower part 35 and 36 connected by a plurality of spaced vertical bars 37 be-

tween two of which is detachably mounted an opaque shield 38 provided centrally with a translucent piece of glass 39, preferably red, which is normally positioned toward the inside of the vehicle. Clear, transparent panes of glass 40 are detachably mounted between the other bars 37 so as to give a clear view to the visual signal mechanism mounted within the lamp.

10 A wooden base 41 is mounted within the lamp bottom 33 and is provided centrally with a bearing plate 42. A lamp cage is rotatably mounted within the lamp casing and comprises a bottom 43 and a top 44 connected by rods 45 and an opaque shield 46 provided centrally with a translucent piece of glass 47 preferably green, which is normally positioned to indicate clear to the rear of the vehicle. The opposite vertical 15 side edges of the shield 46 are rolled, as at 48, see Figs. 4 and 5, to provide a casing for the electric light wires. A white electric lamp 49 is mounted on the bottom 43 of the cage while a red lamp 50 is suspended from 20 the top 44.

51 indicates a bearing mounted on the top 44 and receives the lower end of a shaft 52, said shaft being detachably mounted within the bearing by a set-screw 53. This shaft 52 extends upwardly through a tubular casing 54 carried by the top of the lamp casing and into a housing 55 rotatably mounted on the upper end of the casing 54. A bevel gear 56 is fixed to the upper end of the tubular casing 54 and meshes with a corresponding gear 57 fixed on a shaft 58 loosely journaled in a bearing block 59, which latter is threadedly connected to the upper end of the shaft 52, so as to rotate with it. The upper end of the bearing block is journaled in the top of the housing 55 and is provided with an ornamental cap 60.

The opposite ends of the shaft 58 extend through the walls of the housing 55, one of said ends being provided with an arrow tail-piece 61, while the other is provided with an arrow head-piece 62.

The direction indicator arrow is adapted to normally lie in a horizontal plane, as indicated in Figs. 1 and 2, but by virtue of the particular construction just described, it will be apparent that when the shaft 52 is rocked a quarter of a turn that the arrow will swing from a horizontal to a vertical position in its movement of a quarter of a revolution.

The bottom 43 of the cage is provided centrally with a boss 63 having a reduced trunnion 64 journaled through a bearing plate 65 mounted in the base 41. The bottom 43 is also provided with an oblong recess 66 which receives a pin 67 carried by the outer end of an arm 68 fixed on the upper end of the rock shaft 27 so that each time the rock shaft is actuated by the lever

18, a corresponding movement will be imparted to the lamp cage and the direction indicator arrow mounted on the top of the lamp casing.

The construction of the signal device as just described is simply used in the day time to signal to pedestrians or automobiles the direction in which the driver intends to steer his machine, but at night the electrical illuminating means within the lamp casing is adapted to be used by the closing of a suitable electric switch. 70 75

The shield 46 is normally behind the lamps, so that the white light passes through glass 47 to indicate clear to the traffic in rear, 80 and when the operator desires to turn or stop, the lever 18 is swung so as to turn the shield 46 toward that side of the casing adjacent to the vehicle body thereby exposing the lamps to the rear for indicating danger, 85 when the lamp 50 is lighted. The signal member 62 normally projects forward in a horizontal position when the shield 46 is in its rear position, and when the shield is turned for signaling danger, the signal member 62 is swung outwardly with the shield, 90 and is turned on its axis to a vertical position, as seen in Fig. 3. When the lever 18 is returned, the shield and upper signal member are also returned to normal position. 95

The bottom of each lamp casing is provided with an electric lamp 87 which is so positioned that it will, when lighted, throw its rays on the running-board of the vehicle, so as to enable occupants of the vehicle to clearly see where they are stepping in getting in or out of the vehicle. 100

What I claim is:—

1. A vehicle signal embodying a casing having transparent sides, and a side to be disposed next to the side of the vehicle and provided with a transparent portion, a cage mounted for turning movement within the casing about a vertical axis and including a base, a top and a shield connecting them, said shield having a transparent portion to be moved into registration with the aforesaid transparent portion and to be normally disposed with the shield to the rear, lamps carried by said base and top of different colors, and manual means connected to said base for turning the cage to swing said shield from in rear of the lamps to one side thereof adjacent to the first named transparent portion. 105 110 115 120

2. In a vehicle signal, a lamp casing, a cage mounted for rotation therein and having a shield, a lamp within the cage, a direction indicator having its face in horizontal position mounted on the cage to turn with it and to rotate to present its face in vertical position, means between said indicator and casing for rotating the indicator to present its face in vertical position when it is turned with the cage to a different position, and 130

means connected to the cage for turning it manually.

3. In a vehicle signal, a lamp casing having three transparent sides and a side to be mounted next to the side of the vehicle, an oscillatory cage pivotally mounted in the lamp casing and comprising a base, a top, rods connecting said top and base, an opaque shield also connecting said top and base and carrying a translucent member, lamps carried by said top and base, one of said lamps being red, said shield being normally behind said lamps, and manually operable means for oscillating said cage to swing the shield to one side to expose the red signaling lamp.
4. In a signaling device, a lamp casing having transparent sides, an open sided cage pivotally mounted in said lamp casing, lamps carried by the cage and of different colors, a shield carried by the cage and normally in rear of said lamps, manually operable means for oscillating said cage to move it to one side from in rear of the lamps, a direction indicator having its face in horizontal position mounted on the cage to turn
- 5 with it and rotate to present its face in vertical position, and means for rotating the indicator to present its face in vertical position when the shield is moved from in rear 30 of the lamps.
5. A vehicle signal comprising a supporting bar mounted upon the vehicle dash, a tubular post rising from one end of said supporting bar, a housing mounted on said 35 supporting bar and having tubular connection with said post, a rock shaft rotatably mounted in said post, a rotatable signal supported by the upper end of said post, a connection between said signal and said rock 40 shaft, a lever mounted in said housing, and a connection between said lever and said rock shaft through said tubular housing connection, whereby the signal may be rotated upon actuation of said lever. 45

In testimony whereof I have signed my name to this specification in the presence of two subscribing witnesses.

WILLIAM B. THOMPSON.
